UNITED STATES PATENT OFFICE.

OSCAR L. OWEN, OF WHITINSVILLE, MASSACHUSETTS, ASSIGNOR TO THE WHITIN MACHINE WORKS, INCORPORATED, OF WHITINSVILLE, MASSACHUSETTS.

BELT-SHIPPER.

SPECIFICATION forming part of Letters Patent No. 724,123, dated March 31, 1903.

Application filed June 30, 1902. Serial No. 113,840. (No model.)

To all whom it may concern:

Be it known that I, OSCAR L. OWEN, a citizen of the United States, residing at Whitinsville, in the county of Worcester and State of Massachusetts, have invented a new and useful Improvement in Belt-Shippers, of which the following is a specification.

In the transmission of power to machines by means of a belt a loose and a tight pulley are used. When the machine is in operation, the belt is on the tight pulley, which transmits the power to the machine. When the machine is stopped, the belt is supported on the loose pulley, which is rotated by the belt, but does not transmit the power. In practice the lever operating the shipper requires to be secured to prevent the belt from running from one pulley onto the other, and thereby stop or start the machine when such change is not desired.

In the usual construction of spinning, twisting, and similar machines the driving-shaft projects beyond the end frame and supports the tight and the loose pulleys. To more conveniently control the belt and lock the same in each position, I have devised and produced a belt-shipper mechanism by which the belt is automatically locked against lateral creeping when on the loose as well as when on the tight pulley.

Figure 1 is a top view of the end frame of a spinning-machine, showing my improved belt-shipper. Fig. 2 is an end view of the same. Fig. 3 is a side view of the shipper mechanism, on an enlarged scale, showing one position, and Fig. 4 showing the shipper mechanism in the opposite position.

In the drawings, A indicates the end frame; B B, the pulleys; B', the driving-shaft; B², the outside journal-bearing for the driving-shaft, and B³ the belt. To the end frame A, I secure the bracket c, which is provided with the journal-bearings c' c', in which the actuating-rod c² is journaled. The actuating-rod c² is provided with the hand-levers c³ c³. From the lower part of the bracket c the way c⁴ extends horizontally across the two pulleys.

The slide d is supported on the way c⁴ and has the shipper-bars d' d' secured to it. These shipper-bars are preferably curved and extend beyond each edge of the belt B³. The slide d is connected, by means of the curved arm d², with the lever d³, which is secured on the actuating-rod c² and swings through the opening c⁵ in the bracket c. The toe d⁴ on the lever d³ bears against the bracket c and acts as a stop to arrest the outward movement of the slide. The inward movement of the slide is arrested by the bracket c.

The shipper is operated by turning the actuating-rod c² and through the same the lever d³ through half a revolution, and thereby moving the slide d and the shipper-bars from one position to the other. In either position the slide is locked against accidental movement and holds the belt against creeping. As shown in Figs. 3 and 4, the pivots connecting the curved arm d² with the slide d and the lever d³ are on the same horizontal plane, the curved arm extending over and beyond the rod c² when the parts are in the position shown in Fig. 3.

Having thus described my invention, I claim as new and desire to secure by Letters Patent—

1. In a belt-shipper, the combination with a way, a slide supported on the way, a rotatably-supported rod, and hand-lever on the rod, of another lever secured to the rod, and a curved arm pivotally secured to the latter lever on the rod and to the slide, as described.
2. In a machine of the nature described, the combination with the end frame and the pulleys, of a bracket secured to the end frame, a way extending from the bracket over the pulleys, a sliding support for the shipper-bars on the way, the shipper-bars, a rod supported in bearings on the bracket, hand-levers on the rod, another lever secured to the rod and a curved arm pivotally connected with the slide and the latter lever on the rod, as described.
3. In a belt-shipper, the combination with the bracket c, the bearings c' c' on the bracket, the way c⁴ extending from the bracket, there

being an opening c^5 in the bracket, and the actuating-rod c^2 supported in bearings $c' c'$ on the bracket, of the slide d supporting the shipper-bars, the shipper-bars, the lever d^3 having the toe d^4 and the curved arm d^2 pivotally secured to the slide and the lever d^3 , as described.

In testimony whereof I have signed my name to this specification in the presence of two subscribing witnesses.

OSCAR L. OWEN.
